CLAIM

The ornamental design for a gaming simulator cockpit as shown and described.

DESCRIPTION

FIG. 1 is a top perspective view of my new design; FIG. 2 is another top perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; and, FIG. 9 is an enlarged view of the portion indicated in FIG. 1.

The dash-dash broken lines in the drawings depict portions of the gaming simulator cockpit and form no part of the claimed design. The dash-dot-dash, broken lines in the drawings are included to indicate bounds of the enlargements and form no part of the claimed design.
